UNITED STATES PATENT OFFICE.

MINATOJO SYDNEY, OF CHARLESTOWN, MASSACHUSETTS.

FLYING-MACHINE.

1,250,530.

Specification of Letters Patent. Patented Dec. 18, 1917.

Application filed August 7, 1916. Serial No. 113,478.

To all whom it may concern:

Be it known that I, MINATOJO SYDNEY, a subject of the Emperor of Japan, and a resident of Charlestown, county of Suffolk, and 5 State of Massachusetts, have invented an Improvement in Flying-Machines, of which the following description, in connection with the accompanying drawings, is a specification, like characters on the drawings representing like parts.

This invention relates to aeroplanes designed for carrying persons, freight, etc.

In the drawings Figure 1 is a side elevation of the machine;

15 Fig. 2 is a plan view showing the upper of the two planes;

Fig. 3 is a plan view showing the lower plane;

20 Fig. 4 is a plan view showing the engine and load-carrying platform;

Fig. 5 is a front elevation of a machine;

Fig. 6 is a rear elevation; and

25 Fig. 7 is a detail view of the steering apparatus located in the pilot house at the forward end of the platform.

The machine is made up generally of upper and lower planes 1 and 2 connected by suitable bars and supports 3 and supporting the platform 4 by means of the hangers 5 30 and braces 39.

Depending from the platform 4 are the posts and braces 6 which carry the front and rear wheels 7 and 8 mounted in any usual manner upon axles properly secured to 35 the said posts and braces. Attached to the under side of the forward end of the platform 4 is the usual curved resilient alighting shoe or buffer 9.

40 Mounted upon the forward end of the platform 4 is the pilot house 10 wherein the machine operator may sit and within which are located the various machine controls including the steering gear shown in detail in Fig. 7. Immediately back of said pilot house is 45 the first of the three motor engines 11, 12 and 13, the engine 11 driving the large front propeller 14 which is mounted centrally of the machine in suitable journals attached to the hangers 5 and to the under side of the 50 upper planes 1. The train of shafts and belts connecting the propeller 14 with its engine 11 may be made up of the propeller rotating shaft 15, the belt or chain 16, the intermediate shaft 17, and the belt or chain 55 18, operating in the usual manner.

Also mounted upon the platform 4, near the rear end thereof, is the engine 13 which through the connections 19, 20, 21 and 22 drives the two side propellers. These side propellers are mounted in openings provided 60 therefor in the frames of the lower planes 2 and are indicated by the numeral 23.

Directly ahead of the engine 13 is the engine 12 which through the train of connections made up of the belt or chain 24, shaft 65 25, belts or chains 26 and 27, drives the upper propellers 32 which are mounted upon the shafts 28 and 29 respectively and, projecting through openings 31 in the upper planes, rotate above said planes. 70

Both the upper planes 1 and the lower planes 2 are preferably gutter-shaped, meeting at the longitudinal center of the machine at a slight angle at the front and at a sharper angle at the rear. The rearward ends of the 75 planes 1 and 2 are also bent upwardly forming an angle with the main or forward portion thereof.

At the rearward extremities of the planes are attached in any usual manner as by the 80 hinges 42 and 43 the vertical rudder 33 and the horizontal rudders 34, the latter being cut away at their inside edges to permit the lateral swing of the vertical rudder 33. By any usual train of connections these rudders 85 may be operated from the pilot house 10. Preferably the vertical rudder is operated through its actuating tiller 44, the wires or ropes 35 and hand wheel 36 (see Fig. 7), and the horizontal rudders are operated through 90 their tillers 45, wires or ropes 37, and hand wheel 38.

The shafts 30 upon which the upper propellers 32 are mounted are preferably inclined somewhat toward the front of the machine, thus giving these propellers not only 95 an upward pulling force, but also a forward pulling force.

The forward edges of all parts of the machine including the edges of the planes, the 100 edges of the hangers 5, braces 3, 6 and 39, should be pointed or sharpened to offer the least possible resistance to the air. I have also shown the pilot house 10 constructed with an air-dividing prow at the front for 105 the same purpose.

On the mid rib 30 of the upper planes 1 may be erected posts 40 from which run bracing or stiffening wires 41 to various points of the upper planes. Of course other 110

wires throughout the machine may be used for this purpose, if found necessary or desirable.

An aeroplane constructed in accordance 5 herewith possesses various advantages, some of which are as follows:

The V or gutter-shaped planes prevent lateral sliding of the machine in the air and also act as a preventive of the tendency to 10 rock or turn over sidewise. The upward cant and increased and sharpened angle of the intersecting planes create a channel for the air, the force of which is thereby concentrated against the surfaces of the rudders, 15 resulting in increased promptness in the machine's answering to the helm.

The arrangement of the three separate 20 motor engines, one driving the central forward propeller, another the two upper propellers, and the other the two lateral propellers, results in the minimizing of the dangers attendant upon accidental or necessary 25 stoppage of one or more engines. If the forward engine stops, the machine is not thrown out of balance since the propeller controlled by it is centrally positioned. If 30 the middle engine stops, the machine still retains its balance for the same reason; and so also when the third engine stops since it controls both lateral propellers. Thus a 35 machine so constructed if used in military operations could sustain damage to any one or any combination of its motor engines without the likelihood of upsetting because of resultant unbalanced propelling or lifting force.

The forward inclination of the upper propellers 32 will result in giving the machine some forward driving power even if both the 40 engine driving the main forward propeller and the engine driving the lateral propellers should be put out of commission, thus enhancing the chances of the aviator being able to bring his machine to ground at a desired 45 point without being forced merely to volplane from whatever aerial position he may occupy when the damage is sustained. These upper propellers may also be depended upon partially to counter balance 50 possible perforation of the planes since a part of their force is an upwardly lifting force. The platform 4 affords ample space for carrying freight, provisions, ammunition or passengers while the pilot house 55 incloses and protects the pilot.

These and other advantages will be obvious to those skilled in the art in constructing an aeroplane in accordance with this disclosure.

60 It is obvious that many changes might be made or modifications resorted to in constructing such an aeroplane, without departing from the scope and spirit of my invention, and I do not wish to be understood as confining myself to the specific

structure or structures illustrated and described herein.

I claim:

1. A flying machine comprising in combination two V-shaped planes, the rearward portions of which incline upwardly relatively to the forward portions and are formed in a sharper V than said forward portions to create an intensified air current against the steering apparatus; steering apparatus for guiding the machine to the right and left and up and down, hinged to the rearward ends of said planes; a main driving propeller centrally located at the front of the machine; two lateral driving propellers 70 respectively located to the right and left 75 of the center line of the machine and hung in openings made in the lower planes; two top propellers projecting above the upper planes and somewhat forwardly inclined; 80 and separate engines for driving the main propeller, the lateral propellers, and the top propellers independently.

2. A flying machine comprising in combination an upper plane or planes, a lower plane or planes, the upper and lower planes being respectively arranged to form generally V-shaped channels or troughs, the rearward portions of which are deeper and narrower than the forward portions in order to 95 create an intensified air current upon or about the machine guiding-rudders, said rearward portions being also upwardly inclined relative to the forward portions of 100 said planes; guiding rudders attached to the rearward portions of said planes; lifting and driving top propelling means arranged to rotate upon forwardly inclined axes projecting above the upper planes and over 105 openings made in said planes to permit the unobstructed downward passage of the current of air caused by said propellers; lateral driving propellers hung in openings in the lower planes on each side of the center line of the machine; a main driving propeller centrally mounted at the forward end of the machine; and three independent engines for driving said top propellers, lateral propellers and main forward propeller either independently or in any desired combination.

3. A flying machine comprising in combination generally V-shaped planes, the rearward portions of said planes inclining upward relatively to the forward portions thereof and being also more sharply V-ed than the forward portions to create strong air currents upon or about the machine-guiding means; machine-guiding means attached to said rearward portions of the planes; a main forwardly acting driving means; auxiliary forwardly-acting driving means; and means for simultaneously lifting and driving the machine forward, all 125 said driving and lifting means being ar- 130

- ranged for independent operation or for operation in any desired combination.
4. A flying machine comprising in combination generally V-shaped planes, the rearward portions of said planes inclining upward relatively to the forward portions thereof and being also more sharply V-ed than the forward portions to create strong air currents upon or about the machine; guiding means, machine-guiding means attached to said rearward portions of the planes, and machine-driving means.
5. A flying machine comprising in combination generally V-shaped planes, the rearward portions of said planes inclining upward relatively to the forward portions thereof; machine-guiding means attached to said rearward portions of the planes; a main forwardly-acting driving means; auxiliary forwardly-acting driving means; and means for simultaneously lifting and driving the machine forward, all said driving and lifting means being arranged for independent operation or for operation in any desired combination.
6. A flying machine comprising in combination generally V-shaped planes, the rearward portions of said planes inclining upward relatively to the forward portions thereof, machine-guiding means attached to said rearward portions of the planes, and machine-driving means.
7. A flying machine comprising in combination a plurality of planes, the rearward portions of said planes inclining upward relatively to the forward portions thereof; machine-guiding means attached to said rearward portions of the planes; a main forwardly-acting driving means, auxiliary forwardly-acting driving means; and means for simultaneously lifting and driving the machine forward, all said driving and lifting means being arranged for independent operation or for operation in any desired combination.
8. A flying machine comprising in combination a plurality of planes; machine-guiding means attached to the rearward portions thereof; a main forwardly-acting driving means; auxiliary forwardly-acting driving means; and means for simultaneously lifting and driving the machine forward, all said driving and lifting means being arranged for independent operation or for operation in any desired combination.
9. A flying machine comprising in com-

bination a generally V-shaped plane, the rearward portion of said plane inclining upward relatively to the forward portion thereof and being also more sharply V-ed than the forward portion to create strong air currents upon or about the machine guiding means; machine guiding means attached to said rearward portion of the plane; a main forwardly-acting driving means; auxiliary forwardly-acting driving means; and means for simultaneously lifting and driving the machine forward, all said driving and lifting means being arranged for independent operation or for operation in any desired combination.

10. A flying machine comprising in combination a generally V-shaped plane, the rearward portion of said plane inclining upward relatively to the forward portion thereof; machine-guiding means attached to said rearward portion of the plane; a main forwardly-acting driving means; auxiliary forwardly-acting driving means; and means for simultaneously lifting and driving the machine forward, all said driving and lifting means being arranged for independent operation or for operation in any desired combination.

11. A flying machine comprising in combination a generally V-shaped plane, the rearward portion of said plane inclining upward relatively to the forward portion thereof; machine-guiding means attached to said rearward portion of the plane; and machine driving means.

12. A flying machine comprising in combination the upper plane 1, the lower planes 2, said planes 1 and 2 being generally in the shape of a V increasing in depth and sharpness of inclination toward the rearward end of said planes, machine-guiding means 33 and 34 hinged to the rearward ends of said planes 1 and 2, a main driving propeller 14, auxiliary lateral driving propellers 23 equidistantly positioned from the center line of the machine, and further auxiliary lifting and driving propellers 32 somewhat forwardly inclined to give forward as well as upward power, and separate engine means 11, 12 and 13 mounted to drive the propellers 14, 23, and 32 either simultaneously or in any desired combination.

In testimony whereof, I have signed my name to this specification.

MINATOJO SYDNEY.
